(57) **CLAIM**

I claim the ornamental design for an assembly tool for reusable straws, as shown and described.

DESCRIPTION

FIG. 1 is a perspective view of an assembly tool for reusable straws showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a perspective view of an assembly tool for reusable straws showing my new design in an in-use configuration with the straw shown with a symbolic break in its length. The bottom view forms no part of the design and is omitted. The dot-dash lines represent boundaries of the claimed design. The broken lines showing an assembly tool for reusable straws in form no part of the claimed design.
